CLAIM

The ornamental design for an air compressor shroud, as shown and described.

DESCRIPTION

This case is related to co-pending, commonly assigned U.S. Design Patent Application titled “Air Compressor Shroud”, U.S. patent application Ser. No. 29/292,440, filed on even date.

FIG. 1 is an elevated perspective view of the present air compressor shroud;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken line showing of FIGS. 1-7 is for illustrative purposes only and forms no part of the claimed design or a specified embodiment thereof.
